FLUID FLOW DIVIDER

Edward D. Scheffler, Jr., Coloma, and Laurence H. Fish,
Benton Harbor, Mich., assignors to AG-Chem Equipment Co. Inc.

Filed Feb. 22, 1973, Ser. No. 334,620

Term of patent 14 years

Int. Cl. D23—01

U.S. Cl. D23—40

Fig. 1

Fig. 2

Fig. 3

Fig. 5

Fig. 6

FIG. 1 is a right side elevational view of a fluid flow divider showing our new design.

FIG. 2 is a rear end view thereof.

FIG. 3 is a front view thereof.

FIG. 4 is a bottom view thereof.

FIG. 5 is a left side elevational view thereof.

FIG. 6 is a top plan view thereof.

We claim:

The ornamental design for a fluid flow divider, as shown.
